UNITED STATES PATENT OFFICE.

GILBERT L. CROWELL, JR., OF ARLINGTON, NEW JERSEY, ASSIGNOR TO
DOMINICK & HAFF, OF NEW YORK, N. Y.

DESIGN FOR A SPOON, &c.

SPECIFICATION forming part of Design No. 19,802, dated May 6, 1890.

Application filed March 21, 1890. Serial No. 344,843. Term of patent 7 years.

To all whom it may concern:

Be it known that I, GILBERT L. CROWELL, Jr., of Arlington, in the county of Hudson and State of New Jersey, have invented and produced a new, original, and useful Design for Spoons, of which the following is a description, reference being had to the accompanying photograph, which illustrates the design.

10 The design relates more particularly to the bowl of the spoon, the prominent feature of which is its peculiar outline or contour.

15 The contour of the bowl is in general the oblated outline of a guitar-body, or an oblate oval with incurving sides, and the concavity of the bowl is in general separate parti-spherical concavities opening into one another.

20 The outline or contour of the bowl consists of the broad ovate lip or lip-curve *a a*, the narrower oblate *b b*, these two figures curving inwardly toward and joining each other at

the sides of the bowl, so as to produce the incurvities *c c*.

The bowl-cavity consists of the quartering 25 parti-spherical depressions *d d*, situated on opposite sides of the shank of the spoon-handle, and the similar depressions *e e*, situated at each end of the lip-curve *a a*, which depressions open into one another to form the 30 concavity of the bowl.

The style of the handle of the spoon is immaterial.

What I claim as new is—

1. The design for spoons herein shown and 35 described.

2. In the design for spoons herein shown and described, the oblated outline figure of a guitar-body and the quartering parti-spherical bowl-cavities, substantially as set forth.

GILBERT L. CROWELL, JR.
